[57] CLAIM

The ornamental design for a control panel for a facsimile machine, as shown and described.

DESCRIPTION

FIG. 1 is a top plan view of a control panel for a facsimile machine showing our new design;

FIG. 2 is a front elevational view thereof, the rear elevational view being a mirror image; and,

FIG. 3 is a left side elevational view thereof, the right side elevational view being a mirror image.

The bottom of the control panel is plane and unornamented.

FIG.1

FIG.2

FIG.3
